Company, Webster Groves, Mo., a corporation
of Missouri

No Drawing. Application December 31, 1934,
Serial No. 760,026

7 Claims. (CL 87—12)

This invention relates to a new sulpho-fatty body and to a method of producing the same.

One object of our invention is to provide a new material, composition of matter, or chemical compound, that is capable of various industrial uses, but particularly adapted for use as a substitute for Turkey red oil and the like. Said new material, composition of matter, or chemical compound, may properly be described as a sulpho-fatty body derived by sulphonation of a split unsaturated fatty acid material having at least 6 carbon atoms and less than 16 carbon atoms in the molecule and derived by the thermal decomposition of a body obtained by oxidation of a relatively highly unsaturated fatty body. Briefly, said new material may be described as a sulpho-fatty body derived by the sulphation or sulphonation of certain isologues or homologues of normal hendecenoic acid. The substance or substances sulphonated or sulphated to produce our new material are described in our co-pending application for Patent Serial No. 760,025, filed December 31, 1934. The raw material employed in the sulphonation process and the method of preparing the same are best described by reference to its homologues or isologues, such as normal hendecenoic acid and oleic acid.

Hendecenoic acid is obtained by distilling ricinoleic acid or the glyceride thereof (castor oil) under diminished or atmospheric pressure. It is sometimes known as undecylenic acid. The method of producing this acid is well known and is described in the publication "Dictionary of Applied Chemistry", by Thorpe, 1922. In volume 4, pages 630 and 631 of the said publication the reaction of hendecenoic acid is properly indicated as follows:

but in the text the term "hendecatoic acid" is erroneously used to refer to the product $C_{11}H_{20}O_2$. However, volume 3, page 515 of the said publication properly identifies hendecatoic acid as "undecylic acid" ($C_{11}H_{22}O_2$). In other words, the pyrolytic decomposition of ricinoleic acid or castor oil causes the molecule to break at the hydroxyl position and yields a sulphonatable unsaturated "fatty" acid having 11 carbon atoms. It is understood that the expression "fatty" is here used because the split acid thus obtained is a lower homologue of oleic acid. However, so far as we are aware, this acid does not occur naturally in any fat or oil. For reasons which will be subsequently obvious, we shall refer to hendecenoic

acid derived from castor oil as "normal" hendecenoic acid.

In our aforementioned co-pending application we have described the production of materials similar to ricinoleic acid insofar that they contain an ethylene linkage and a hydroxyl radical in the hydrocarbon fatty chain. Briefly stated, the process there described consists in subjecting a relatively highly unsaturated fatty acid or fatty body having an iodine number of 120, or higher, and derived from the class of semi-drying, drying and marine oils to oxidation or blowing with air, particularly moist air, so as to decrease the iodine number to $\frac{1}{2}$ or $\frac{1}{3}$ of its original value, with a subsequent increase in acetyl value, or at least 15 with the formation of oxy bodies. Unsaturated oxidized bodies, so produced, are then subjected to thermal decomposition to yield homologues or isologues of normal hendecenoic acid in the same manner essentially that normal hendecenoic acid is derived from ricinoleic acid or from castor oil. It is immaterial whether the products thus obtained are in the form of fatty acids, or in the form of glycerides or a mixture of the same, and it is immaterial whether the relatively highly 25 unsaturated material, prior to oxidation, be in the form of a fatty acid or a glyceride or a mixture of same.

The raw material that we prefer to use in producing the new sulpho-fatty bodies that constitute the subject-matter of our present application for patent, is derived by the thermal decomposition of oxidized or blown marine oils, particularly sardine oil. In order that said raw material may be readily prepared without reference to any other source of information, we give the following procedure for preparing said raw material: The blowing process and the thermal decomposition are preferably conducted in the same vessel, purely as a matter of convenience. Our preference is to employ 500 or 1,000 lbs. of sardine oil, blow the same with moist air at approximately 150 to 250° until there is a drop in iodine number to approximately $\frac{1}{2}$ or $\frac{1}{3}$ of the original iodine value, and a rise in acetyl value or absorption of oxygen corresponding to the drop in the iodine value. At the completion of the blowing process the moist air is shut off and the temperature raised with slightly reduced pressure, so as to thermally decompose the oxidized sardine oil. The aldehyde-like materials which distill over are condensed and employed for any suitable purpose. The loss in weight of the residue during thermal decomposition should not exceed, as a rule, 10% or 5%

12% by weight, of the original oxidized sardine oil.

As previously stated, the sulphonation of the constituents of the raw material is best understood by reference to the sulphonation or sulphation of their homologues or isologues, such as normal hendecenoic acid or its glyceride and oleic acid or its glyceride. Normal hendecenoic acid can be subjected to sulphonation in the various manners applied in the sulphonation of its higher homologue, oleic acid.

It is well known that oleic acid may be sulphonated at a relatively low temperature, for instance, 35°, or less, with 66° Baumé sulphuric acid to yield a fatty acid sulphate, i. e., oleic acid hydrogen hydrogen sulphate. It is also known that oleic acid may be sulphonated at or near the boiling point of water with sulphuric acid; or at a lower temperature with an onium compound of sulphuric acid to yield a true sulphonic acid. Such true sulphonic acids are differentiated from fatty acid sulphates above referred to by the fact that they do not decompose on boiling with dilute hydrochloric acid. Another well known procedure for sulphonating oleic acid, is to sulphonate in the presence of a suitable aromatic compound, such as benzene, phenol, naphthalene, beta naphthol, etc., so as to produce a sulpho aromatic "fatty" acid. Such sulphonation products are characterized by the presence of a sulphonic acid radical, but said sulphonic acid radical is attached to the aromatic nucleus and not directly to the hydrocarbon fatty chain of the fatty acid.

Although one can produce pure sulpholeic acid, i. e., oleic acid hydrogen hydrogen sulphate, yet the expression sulpholeic acid is most commonly employed in the arts to indicate the commercial product obtained by sulphation or sulphonation of oleic acid which contains, for example, not only oleic acid hydrogen sulphate, but also the hydrolytic decomposition product, i. e., hydroxystearic acid, and also products obtained by the auto-esterification of hydroxystearic acid, such as hydroxystearyl hydroxystearic acid. Unreacted oleic acid or its ester derived by reaction with hydroxystearic acid may be present. Lactones may be present. Sulphonated poly acids may be present. Sulpholeic acid may be almost free from sulphur-containing constituents. Similarly, the sulphonation employed in the manufacture of a true sulphonic acid or a sulpho-aromatic fatty acid, is accompanied by similar hydrolytic decomposition products and other products obtained by the esterification of or etherization of the hydroxylated bodies present. In the same manner that the expression sulpholeic acid has been used broadly to indicate sulpho derivatives obtained by all three of these processes, together with the accompanying materials, similarly the expression "normal sulpho-hendecenoic acid" is herein employed in the same analogous manner to indicate the analogous products obtained from normal hendecenoic acid alone or in presence of such reactive aromatic compounds as benzene, phenol, naphthalene, beta naphthol, etc.

The unsaturated fatty acids employed as raw materials to produce the sulpho-fatty acids herein described, are characterized by having at least 6 carbon atoms and less than 16 carbon atoms, and being free or substantially so from hendecenoic acid. As previously stated, they represent isologues or homologues of normal hendecenoic acid and enter into the above three types of sulphonation or sulphation which has been

described in respect to oleic acid and normal hendecenoic acid. Since the exact composition of the raw materials are unknown except to the extent that they are unsaturated fatty acids having less than 16 carbon atoms and more than 6 carbon atoms in the molecule, one cannot exactly state their chemical composition, except as noted that they may be sulphated or sulphonated to produce sulphonic acids, fatty acid sulphates or sulpho-aromatics. Furthermore, there are certain hydrolytic reactions which take place during sulphonation with the formation of hydroxy acids, and said hydroxy acids react further to give lactones, poly acids, etc. In the same analogous manner as is true in the sulphonation or sulphation of normal hendecenoic acid or oleic acid. Various salts, esters, etc. may be formed from the sulpho bodies in the usual manner, i. e., one may produce water-soluble salts, such as sodium salts, potassium salts, ammonium salts, or salts derived from basic amines, such as triethanolamine, water-insoluble calcium salts, etc. Esters may be formed, such as ethyl ester, methyl ester, propyl ester, butyl ester, etc.

Purely for the sake of convenience we will refer to the raw material, prior to sulphonation, as "isohomohendecenoic acid", because, in view of the method of preparation, and in view of the chemical reactions which these raw materials undergo, they appear to be isologues or homologues of hendecenoic acid, and therefore, in the absence of more suitable nomenclature, the coined word "isohomohendecenoic" acid will be employed. Similarly, the new composition of matter forming the subject-matter of the present application for patent will be referred to as "sulpho-isohomohendecenoic acid". The word "sulpho" is employed in the same manner that the word "sulpholeic acid" is commonly employed in the arts, i. e., to mean the product obtained by sulphonation in any of the various manners described, plus the accompanying product, and not to mean the fatty acid sulphate derived at low temperature, which might also be termed "sulpho" isohomohendecenoic acid.

What is said in our co-pending application for patent Serial No. 760,024, filed Dec. 31, 1934, in regard to the sulphonation of normal hendecenoic acid, applies in an analogous manner to the sulphonation of isohomohendecenoic acid herein contemplated. In the said co-pending application there appears the following statement in regard to the sulphonation of normal hendecenoic acid:

"The sulphonation of hendecenoic acid must be handled cautiously so as to prevent polymerization with the formation of insoluble, gummy or resin-like products. This can be accomplished most readily by a relatively low temperature sulphonation, such as 10° C. or less, the use of sulphuric acids of strengths slightly less than 66° Baumé, or else sulphonation in the presence of organic anhydrides, such as acetic anhydride. Sulphonation in the presence of a molecular amount of a readily sulphonatable aromatic compound, such as phenol, is also a suitable procedure.

When the sulphonated mass obtained by sulphonation in absence of an aromatic compound, is diluted with water there is a decomposition or hydrolysis of some of the fatty acid sulphate if present. The fatty acid sulphate referred to is hendecenoic acid hydrogen hydrogen sulphate, which may also be characterized as a substitu-

tion product of the saturated hendecolic acid and may be considered hydrogensulphate hendecolic acid, i. e., an acid in which one hydrogen of hendecolic acid (undecylic acid) has been replaced by a hydrogen sulphate radical. Thus, the decomposition product obtained by hydrolysis of hydrogen sulphate hendecolic acid is hydroxy hendecolic acid, and the poly acid obtained by autoesterification of two moles of hydroxy hendecolic acid is hydroxy hendecoyl hydroxy hendecolic acid. The analogy to the formation of hydroxystearic acid, poly acids, lactones, sulphated poly acids, etc. therefrom is evident".

15 What has been said in the above-mentioned excerpt from our co-pending application for patent Serial No. 760,024, filed December 31, 1934, in regard to the sulphation or sulphonation of normal hexadecenoic acid or its esters, applies 20 with equal force and effect to the sulphation or sulphonation of isohomohendecenoic acid, as is herein described. The same analogous sulphation or sulphonation reactions take place; the same analogous hydrolytic reactions take place; 25 the same analogous esterification or polymerization reactions take place; and the same analogous compounds are formed, but are different isomerically and probably different in the number of carbon atoms present also.

30 It is well known that when reagents such as sulphisophomohendecenoic acid are prepared and have both a carboxyl hydrogen and a sulphonate hydrogen that only the sulphonate hydrogen need be neutralized if desired. Thus, one 35 may produce a half salt in which the carboxyl hydrogen is unneutralized, but one may also produce mixed salts, in which the sulphonate hydrogen is replaced by one metallic atom, such as sodium atom, and the carboxylic hydrogen is replaced by some dissimilar atom or radical, such 40 as an ammonium radical. Similarly, one may produce a mixed ester, etc.

45 Since isohomohendecenoic acid is sulphated or sulphonated in the same manner as oleic acid or normal hexadecenoic acid, the sulphation or sulphonation of which incidentally is described 50 in our first mentioned co-pending application, and also in U. S. Patent No. 1,749,463, to Bertsch, dated May 4, 1930, it hardly appears necessary 55 to describe the manufacture of the new composition of matter, because it is only necessary to apply such conventional processes to the raw material described in our last mentioned co-pending application and which has previously been 60 briefly summarized. However, as an example, we will state that we prefer to obtain 500 lbs. of isohomohendecenoic acid derived by the thermal decomposition of oxidized sardine oil, prepared as previously described, and mix the same with 65 150 lbs. of acetic anhydride, and then sulphonate the same with 500 lbs. of concentrated sulphuric acid at a temperature of not over 10° C. The reaction mixture resulting from said sulphonation or sulphation process is washed in the cold with twice its volume of concentrated Glauber's salt 70 solution, and after complete separation, the upper layer is withdrawn and at least partially neutralized with ammonium hydroxide, so that the final mixture is an ammonium sodium salt of a kind wherein the sulphonate hydrogen is replaced by a sodium atom and the carboxylic hydrogen at least partially replaced by an ammonium radical.

75 Such materials may be used as substitutes for

Turkey red oil, as previously stated, and they may also be used as a demulsifying agent in the resolution of crude petroleum emulsions of the water-in-oil type. It has been so common to use a demulsifying agent derived from an ester in the form of a salt, or in the form of an ester, that the expression "acid body" is frequently used to mean the acid itself or an ester thereof, or a salt thereof. The word "body" is herein employed in this same sense in conformity with its prior 10 usage in the art.

It is to be understood, that isohomohendecenoic acid, i. e., the product which is subjected to sulphonation or sulphation, need not be derived from sardine oil, but may be derived from any 15 marine oil of commerce or from any semi-drying or drying fatty oil or the corresponding fatty acid. Sardine oil is preferably employed because of its low cost, uniformity and ease of oxidation. It should also be understood that the sulphonation of the isohomohendecenoic acid or the split acid derived from oxidized sardine oil, need not be conducted in the manner above described to give fatty acid sulphates, but it may be conducted in a manner so that the sulpho derivative 20 is in the form of a true sulphonic acid or in the form of a sulpho-aromatic fatty acid.

Having thus described our invention, what we claim as new and desire to secure by Letters Patent is:

30

1. A new composition of matter, consisting of a sulpho derivative of an unsaturated, saponifiable, fatty acid material, said unsaturated, saponifiable, fatty acid material having at least 6 carbon atoms and less than 16 carbon atoms in 35 the molecule, and derived by thermal decomposition of a body obtained by the oxidation of a relatively highly unsaturated fatty body; said fatty body, prior to oxidation, being characterized by an iodine number of not less than 120 and 40 not more than 190, said oxidation being conducted at a temperature range of from 150° C. to 250° C., by means of air until there is a drop in the iodine number to a value of not over two-thirds the original iodine number and a corresponding 45 increase in the acetyl value; and said thermal decomposition being conducted at a temperature range of from 270° C. to 330° C., with a loss in weight of not over 12%.

2. A new composition of matter, consisting of 50 an acidic, sulpho derivative of an unsaturated, saponifiable, fatty acid material; said unsaturated, saponifiable, fatty acid material having at least 6 carbon atoms, and less than 16 carbon atoms in the molecule, and derived by thermal 55 decomposition of a body obtained by the oxidation of a relatively highly unsaturated fatty body; said fatty body, prior to oxidation, being characterized by an iodine number of not less than 120 and not more than 190, said oxidation being conducted at a temperature range of from 150° C. to 250° C., by means of air until there is a drop in the iodine number to a value of not over two-thirds the original iodine number and a corresponding increase in the acetyl value; and said thermal decomposition being conducted at a 60 temperature range of from 270° C. to 330° C., with a loss in weight of not over 12%.

3. A new composition of matter, consisting of a neutralized, sulpho-derivative of an unsaturated, saponifiable, fatty acid material; said unsaturated, saponifiable, fatty acid material having at least 6 carbon atoms and less than 16 carbon atoms in the molecule, and derived by thermal 70 decomposition of a body obtained by the oxidation 75

of a relatively highly unsaturated fatty body; said fatty body, prior to oxidation, being characterized by an iodine number of not less than 120 and not more than 190, said oxidation being conducted at a temperature range of from 150° C. to 250° C., by means of air until there is a drop in the iodine number to a value of not over two-thirds the original iodine number and a corresponding increase in the acetyl value; and said thermal decomposition being conducted at a temperature range of from 270° C. to 330° C., with a loss in weight of not over 12%.

4. A new composition of matter, consisting of a neutralized sulpho-derivative of an unsaturated, saponifiable, fatty acid material; said unsaturated, saponifiable, fatty acid material having at least 6 carbon atoms and less than 16 carbon atoms in the molecule, and derived by thermal decomposition of a body obtained by the oxidation of a relatively highly unsaturated fatty body; said fatty body, prior to oxidation, being characterized by an iodine number of not less than 120 and not more than 190, said oxidation being conducted at a temperature range of from 150° C. to 250° C., by means of air until there is a drop in the iodine number to a value of not over two-thirds the original iodine number and a corresponding increase in the acetyl value; and said thermal decomposition being conducted at a temperature range of from 270° C. to 330° C., with a loss in weight of not over 12%, neutralization being accomplished by means of an inorganic base.

5. A new composition of matter, consisting of a neutralized sulphate compound of an unsaturated, saponifiable, fatty acid material, said unsaturated, saponifiable, fatty acid material having at least 6 carbon atoms and less than 16 carbon atoms in the molecule, and derived by thermal decomposition of a body obtained by the oxidation of a relatively highly unsaturated, fatty body; said fatty body, prior to oxidation, being characterized by an iodine number of not less than 120 and not more than 190, said oxidation being conducted at a temperature range of from 150° C. to 250° C., by means of air until there is

a drop in the iodine number to a value of not over two-thirds the original iodine number and a corresponding increase in the acetyl value; and said thermal decomposition being conducted at a temperature range of from 270° C. to 330° C., with a loss in weight of not over 12%, neutralization being accomplished by means of an inorganic base.

6. A new composition of matter, consisting of a neutralized sulphate compound of an unsaturated, saponifiable, fatty acid material, said unsaturated, saponifiable, fatty acid material having at least 6 carbon atoms and less than 16 carbon atoms in the molecule, and derived by thermal decomposition of a body obtained by the oxidation of sardine oil, said oxidation being conducted at a temperature range of from 150° C. to 250° C., by means of air until there is a drop in iodine number to a value of not over two-thirds of the original iodine number and a corresponding increase in the acetyl value, and said thermal decomposition being conducted at a temperature range of from 270° C. to 330° C., with a loss in weight of not over 12%, neutralization being accomplished by means of an inorganic base.

7. A new composition of matter, consisting of a sulphate compound of an unsaturated, saponifiable, fatty acid material having at least 6 carbon atoms and less than 16 carbon atoms in the molecule, and derived by thermal decomposition of a body obtained by the oxidation of sardine oil, said oxidation being conducted at a temperature range of from 150° C. to 250° C., by means of air until there is a drop in iodine number to a value of not over two-thirds of the original iodine number and a corresponding increase in the acetyl value, and said thermal decomposition being conducted at a temperature range of from 270° C. to 330° C., with a loss in weight of not over 12%, neutralization being accomplished by means of ammonium hydroxide.

MELVIN DE GROOTE.
